SPHERODIZER

John C. Sherwin, South San Francisco, Calif., assignor to the United States of America as represented by the Secretary of the Navy

Application March 23, 1955, Serial No. 496,361

3 Claims. (Cl. 263—21)

(Granted under Title 35, U. S. Code (1952), sec. 266)

This invention may be manufactured and used by or for the Government of the United States of America for governmental purposes without the payment of any royalties thereon or therefor.

This invention relates to aerosol apparatus, and more particularly to an apparatus for producing an aerosol sample containing spherical particles.

In conducting laboratory radioactive contamination-decontamination scale studies, it is necessary to provide aerosol samples simulating the actual particulate matter or fall-out produced by an underground or shallow underwater atomic explosion. It has been determined that such radioactive particles are glassy spheres in an environment of inert particles.

Several different types of apparatus have been proposed for this purpose but, generally speaking, they have involved the handling of large quantities of low activity materials as well as excessive number of steps in the making, collecting and mixing of radioactive spheres with the gross material. Further, these procedures entail the necessity for storing the mixture until used.

A principal object of this invention is to provide a single apparatus which will produce an aerosol sample of spherical particles and a corollary object is to simultaneously mix the spherical particles with a second particulate matter to produce a desired aerosol.

Another object is to provide such an apparatus in which the cycle of operation is continuous.

Further objects are to provide an apparatus which is simple and inexpensive in initial cost and operation.

These and other objects will become apparent from the detailed description and the accompanying drawing.

The foregoing objects of this invention are accomplished by an apparatus generally comprising a combustion chamber in which can be formed radioactive spherical particles, the particles then being mixed with another particulate matter and the mixture discharged from the apparatus.

In one specific embodiment, the apparatus is formed of inner and outer concentrically spaced open-ended tubular members having an annular passage therebetween through which is propelled an inert particulate matter. The inner tube is a combustion chamber being provided with a flame producing means into which is introduced a second particulate matter capable of being melted and formed into spherical particles. The inner tube extends short of the mouth of the outer tube to form a chamber for mixing the inert particulate matter and the spherical particles, the latter particles being formed as they are drawn through the combustion chamber and subsequently discharged from the apparatus in the mixture.

In the drawing, Fig. 1 is a side elevation of the assembled apparatus constructed according to the invention; Fig. 2, a longitudinal section of the apparatus, and Fig. 3, an enlarged transverse section taken along line III—III of Fig. 1.

Referring to the drawing, the apparatus, which is gen-

2

erally indicated by the numeral 10, comprises a pair of inner and outer open-ended tubular members 12 and 14, connected together in spaced concentric relation by webs 16. To provide a carrier for the radioactive spherical particles later to be described, an inert, non-radioactive particulate matter represented by arrow 17, is introduced under pressure into passages 18 through a hose 20 and subsequently expelled from a tube nozzle 22 in a mixture with the radioactive particles represented by arrow 23.

10 Inner tube 12 constitutes a chamber where radioactive spherical particles are formed in a heating and cooling process, one suitable heating means being a conventional oxy-acetylene torch 24, having oxygen and acetylene pipes 26 and 28 projecting through outer tube 14. As such a flame will produce temperatures of approximately 6000° F., it is preferred that inner tube 12 be constructed of stainless steel and provided with cooling fins 29. A powder cutting adapter 30 is threaded around a torch nozzle 32, and the nozzle assembly is seated in the rear end of inner tube 12. The bore of adapter 30 is concentrically spaced from nozzle 32 for providing discharge passages 34 about nozzle jets 36. Passages 34, which, in reality, are a series of radially-spaced holes, are communicated with a suitable source of radioactive particulate matter, not shown, this matter being carried by an oxygen stream and ejected from passages 34 into the combustion chamber in the direction of arrows 38. The radioactive matter may be a mixture of soil particles and any radioactive material to be tested, the soil particles capable of being melted in the oxy-acetylene flame. The gas mixture discharged into inner tube 12 from nozzle jets 36 is ignitable by a spark plug 39 connected to a suitable source of power, such as a battery 40 and a transformer 42 (Fig. 1).

35 The radioactive matter in the illustrated embodiment is introduced into the combustion chamber in the same general direction as the oxy-acetylene gases, and it is apparent that the particles have a straight flow through the flame as they are being melted and formed into spherical particles. However, if it is desired to melt larger sized particles than normally could be accommodated with the above assembly, this can be accomplished by introducing the particles in a counterflow to the oxy-acetylene gases, in which case the particles would be propelled into the flame and after propelling force has been dissipated they would reverse their path and flow concurrent with the flame. Thus, the larger particles would remain in the hottest position of the flame for a longer period of time and would have more opportunity to melt.

60 Although operation of the apparatus probably is obvious from the drawing, it will be briefly described. After the oxy-acetylene flame has been properly set and the inner tube 12 has attained a red heat, the flow through the pipe 20 is initiated. The inert non-radioactive material flow 17 is propelled through passages 18 and discharged from nozzle 22. Simultaneous with the above flow, the radioactive particles in flow 37 are ejected into the flame through passages 34 and are heated above their melting point in transit through the combustion chamber so that, upon leaving the hot area of the flame they solidify into spherical particles. When the radioactive spherical particles reach the end of the inner tube 12, they are mixed in chamber 44 formed between the end of tube 12 and tube 14 and finally they are discharged through nozzle 22 with the inert material. The discharged material can be directed in any manner depending on the type of contamination-decontamination studies to be conducted.

65 The foregoing apparatus enables the formation of spherical particles, the mixing of these particles and dispersion of the mixture, all in a simple and expeditious

manner. These operations are carried on in a continuous cycle eliminating separate and independent operations, and the stowage of intermediate mixtures.

Obviously, many modifications and variations of the present invention are possible in the light of the above teachings. It is, therefore, to be understood that within the scope of the appended claims the invention may be practiced otherwise than as specifically described.

I claim:

1. Apparatus for forming and mixing particulate matter comprising an outer tubular member having inlet and outlet ends, a material supply means coupled to said inlet end for introducing a particulate matter into the member and propelling it through said outlet end, an inner tubular member concentrically disposed in spaced relationship within said outer member for forming an annular passageway for said material, said inner member terminating short of said outer member discharge end for providing a mixing chamber formed by the portion of said outer member extending beyond said inner member, said portion converging into a discharge funnel of substantially the cross-sectional area of the inner member, said inner member opening into said mixing chamber and having its other end closed, flame-producing means mounted in said closed end, and a second material supply means communicated with said inner tubular member for delivering a second particulate matter into said member, said flame being capable of coalescing meltable matter into spheres prior to discharge into said mixing chamber, whereby said spheres are discharged from said chamber in an atmosphere of the particulate matter propelled through said outer tubular member.

2. Apparatus for forming and mixing particulate matter comprising an outer tubular member having inlet and outlet ends, a material supply means coupled to said inlet end for introducing a particulate matter into the member and propelling it through said outlet end, an inner tubular member concentrically disposed in spaced relationship within said outer member for forming an annular passageway for said material, said inner member terminating short of said outer member discharge end for providing a mixing chamber formed by the portion of said outer member extending beyond said inner member, said portion converging into a discharge funnel of substantially

the cross-sectional area of inner member, said inner member opening into said mixing chamber and having its other end closed, flame-producing means mounted in said closed end, and a second material supply means mounted in said closed end concentrically about said flame-producing means for delivering a second particulate matter into said inner tubular member, said flame being capable of coalescing meltable matter into spheres prior to discharge into said mixing chamber, whereby said spheres are discharged in an atmosphere of the particulate matter propelled through said outer tubular member.

3. Apparatus for forming and mixing particulate matter comprising an outer tubular member having inlet and outlet ends, a supply of particulate matter, means for introducing said particulate matter under pressure into said inlet end and propelling it through said outlet end, an inner tubular member concentrically arranged in spaced relationship within said outer member for forming an annular passage for said material, said inner member terminating short of said outer member discharge end for providing a mixing chamber formed by the portion of said outer member extending beyond said inner member, said portion converging into a discharge funnel of substantially the cross-sectional area of said inner member, said inner member opening into said mixing chamber and having its other end closed, flame-producing means mounted in said closed end, a second supply of particulate matter, a second material supply means communicating said second supply with said inner tubular member concentrically about said flame-producing means for introducing into said inner member said second particulate matter, said flame being capable of coalescing meltable matter into spheres prior to discharge into said mixing chamber, whereby said spheres are discharged in an atmosphere of said particulate matter propelled through said outer chamber.
